TO CRANE COMPANY, OF CHICAGO, ILLINOIS, A CORPORATION OF ILLINOIS.

FURNACE-CHARGING APPARATUS.

1,177,143.

Specification of Letters Patent.

Patented Mar. 28, 1916.

Application filed January 6, 1914. Serial No. 810,570.

To all whom it may concern:

Be it known that we, EUGENE A. RUDOLF and WILLIAM W. DOOLITTLE, citizens of the United States, and both residing at Chicago, 5 in the county of Cook and State of Illinois, have invented certain new and useful Improvements in Furnace-Charging Apparatus, of which the following is a full, clear, and exact specification, reference being had 10 to the accompanying drawings.

Our invention has reference to apparatus for charging blast furnaces, or the like; and it has for its primary objects the provision of an improved furnace charging apparatus, 15 wherein the charge may be quickly delivered and unloaded at the charging door of the furnace, and the empty charge container or skip readily retracted therefrom; the provision in a furnace charging apparatus of co- 20 operating charge receiving and conveying means adapted to deliver the charge to the furnace, wherein the conveying means has easy and positive movement along the charging floor to advance the charge container to 25 points directly over the charging hole or door of the furnace, and wherein the receiving means has movement relative to the conveying means whereby to unload the charge; and the provision in a furnace 30 charging apparatus of the character just specified, of means for advancing and re- 35 tracting the conveying means and independently operable means for tilting the receiving means, whereby the charge may be un- 40 loaded into the furnace at a time when the conveying means is brought to a standstill at any desired point over the charging door, or while it is in movement.

Our invention also contemplates certain 45 novel details of construction and arrangement of parts for guiding and controlling the linear and axial movement of the charge receiving carrier, and in a manner to obtain the highest degree of ease and efficiency in the unloading operation of the apparatus.

The foregoing, together with such other objects as may hereinafter appear, or are incidental to our invention, we obtain by means of a construction illustrated in preferred form in the accompanying drawings, 50 wherein:

Figure 1 is a side elevation of one form of apparatus embodying our invention, and

illustrating its application to the cupola of a furnace;

Figures 2 and 3 are front and rear end elevations of the showing in Figure 1;

Figure 4 represents a plan view of Figure 1;

Figure 5 is an enlarged view of the charge receiving carrier shown at the left of Figure 1; and,

Figure 6 is a transverse section through Figure 5 and taken on the line VI—VI in the direction indicated by the arrows.

In the drawings we have illustrated the application of one embodiment of our invention to the cupola A of a furnace, in which case it is customary to elevate the charge container or skip B up an incline, 70 or by means of an elevator (not shown), to the charging platform C, which latter leads to the charging door or hole D of the cupola A, and is provided with the tracks E which are flush with the floor and terminate adjacent the rim of the hole D.

Our invention particularly resides in the charging apparatus, of which the means for receiving the skip after its arrival on the platform C, and for conveying it to the charging door D for unloading will now be described.

The conveying means or carrier is indicated as a whole at F in Figure 1, and is provided with a frame comprising the vertically extending and rearwardly inclined side members 7, 7, and 8, 8, respectively, each pair of intersecting members 7 and 8 being rigidly fastened together intermediate their ends as in the manner indicated at 9 in Figures 5 and 6.

The vertical side members 7, 7, have their upper ends connected together by the transverse bar 10, and their lower forked ends are provided with bearings 11, 11, in which are journaled the wheels 12, 12, for travel along the platform tracks E. Similarly, the other component members 8, 8, of the frame are joined together at their upper ends by the transverse bars 13. By means of this construction and arrangement of the parts a strong and rigid carrier frame is obtained.

The diagonal side members 8, 8, which incline upwardly from a point forward of the members 7, 7, to a point well to the rear and

above them, are preferably constructed of commercial shaped iron of channel section, and have at their upper terminals stop brackets or arms 14, 14, which carry the axle of 5 the wheels 15, 15, that are provided to travel along and between the short overhead guides or tracks 16. These tracks, preferably channel irons, may be supported or suspended in any desired manner, depending upon local 10 conditions, or as in the manner indicated in Figure 1 where the tracks 16 have their inner ends carried in the side of the building, and have their free ends supported by vertical side bars 17^a from the superstructure 15 which may include the channel irons 17, 17, extending between the I beams, which latter are intended to be carried in the walls of the building.

As the skip containing the charge reaches 20 the platform, at the right of Figure 1, it enters into and is received by a box-like receiving frame in the carrier, indicated as a whole at H in Figure 1, which receiving frame is disposed to extend longitudinally 25 and intermediately of the lower ends of the main frame of the carrier F and by which it is carried. The box-like frame, the construction of which is perhaps better shown in Figures 4, 5 and 6, comprises the side 30 plates 18 provided with the angle irons 19 which constitute upper and lower guiding tracks for the wheels of the skip, the bottom plate 20, and the forward end plate 21, both bottom and end plates being suitably fastened to the side plates. The top and rear 35 ends of the box H are both open.

As previously indicated, our invention contemplates that the skip receiving device H be carried in the carrier F and capable of 40 tilting movement with respect to the carrier frame. With this end in view, the rear end of the box H is hung from the side frame members 7, 7, by means of the side lugs or stop pieces 22, 22, which project outwardly 45 from the sides of the box to bear or rest upon the oppositely extending abutments 23, 23, formed on the lower ends of the side members 7, 7, as best shown in Figure 3.

The front end of the box H is pivotally 50 suspended or carried from the lower ends of the diagonal side members 8 in the manner indicated in Figure 5, wherein bearing brackets 24 and 25, connected by pivot pins 26, are respectively mounted on the side of the 55 box and on the adjacent end of the side member 8, and at both sides of the carrier. It will be apparent from the description thus far made, that the application of a force tending to lift the rear end of the box will 60 move it on an arc, the axis of this movement being at the line of the pins 26 at the forward end of the box. While this tilting movement is of course communicated to the skip so that the charge therein may be 65 dumped through its open front end, it will

be clear that any movement of the skip relative to the box is prevented by the front plate 21 and angles 19.

In order to impart movement to the carrier F along and between its parallel tracks 70 for the purpose of delivering its charge and returning the then empty skip, we provide the connected levers 27 which are pivotally suspended at 28 from the cross beams 17, and are vibrated about the pivotal point 28 75 by the piston 29 of any suitable reciprocating means, such as the fluid operated device indicated at K. The to-and-fro motion thus imparted to the levers 27 is in turn transmitted to the carrier F through the link 80 mechanism 30 which connects the said levers with the frame members 8.

In this way the charge receiving carrier has free and easy movement with its rear 85 wheels 12 on the lower pair of tracks, and has its forward end supported or suspended in true longitudinal relation by the provision of the wheels 15 which travel along and are guided by the overhead tracks. Consequently the open front end of the skip may 90 be brought to a point well over and beyond the axis of the charging door or hole D for the purpose of spreading or properly distributing the charge, in which case the set of parallel tracks co-operate to maintain the 95 carrier in its proper horizontal relation.

The means for tilting the box H and with it the skip will now be described. A suitable reciprocating means, such as the fluid operated device M, is preferably carried on 100 the levers 27 and pivotally mounted at its upper end intermediate these members, and has its piston connected to a yoke member 31 whose arms have hubs 31^a which fit loosely about bosses 32 formed on the rear end of 105 the box H.

The air connections for the reciprocating devices K and M are not shown, as they are intended to separately lead from these devices to cocks or valves adjacently positioned in any desired location which may offer convenience in operation, such location in each case depending upon local conditions.

The operation of the apparatus may be briefly described as follows:—Considering the carrier in retracted position as indicated in the dotted lines at the center of Figure 1, and carrying the loaded skip, actuation of the air device K will impart movement to the carrier to advance it toward the charging door D up to the full extent of the forward movement of the piston rod 29 if desired. The range of advance is entirely within the control of the operator, and the carrier may be stopped at any suitable point over the hole and the box H tilted by operating the air device M, or it may be tilted while the carrier is still in movement over the charging door in order 120 125 130

to properly spread the charge contained in the skip, as will be readily understood. Reverse actuation of the air devices K and M returns the empty skip and its carrier to the same position as before.

5 We do not intend to restrict ourselves to exact details of construction, nor to the precise arrangement of the various parts as shown, for it is obvious that variations may 10 be made therefrom without in any way departing from the spirit and scope of the invention as more particularly pointed out in the appended claims.

From the foregoing, the essential features, 15 elements and operation of the apparatus together with its simplicity and other advantages thereof, will be clearly apparent to those skilled in the art.

Having thus described our invention and 20 illustrated its use, what we claim as new and desire to secure by Letters Patent, is the following:—

1. A charge delivering device comprising a frame having two relatively fixed axes of 25 support, and wheels journaled in said frame at the respective axes and adapted to support the front and rear ends of the frame, the supporting axis for the front end of the frame being located above and to the rear of 30 the rear supporting wheels, substantially as described.

2. In combination, a charge delivering device comprising a frame having two fixed axes of support, wheels journaled in said frame at the respective axes and adapted to support the front and rear ends of the frame, and a guide means for the device, the supporting axis for the front end being located above the rear supporting axis and 40 having its wheel or wheels engaging the said guide means.

3. In combination, a charge delivering device comprising a frame having two axes of support, wheels journaled in said frame at the respective axes and adapted to support the front and rear ends of the frame, and means for imparting movement to the device, said means being connected with the frame at a point intermediate its said axes.

50 4. A furnace charging apparatus, consisting of a charge delivering device provided with wheels adjacent its rear end, a guide-track mounted on a suitable support, means coöperating therewith to support the front end of the device comprising a member extending upwardly therefrom to have a slide- 55 able engagement with said track, and means for advancing or retracting the device including as a member thereof a lever pivoted on said support and having a link connection with said upwardly extending member.

55 5. In combination, a charge delivering device provided with supporting wheels adjacent its rear end, a guide means mounted on a suitable support above said device, a

rigid connecting member extending from the device to slidably engage the said guide means, and coöperating therewith to guide and sustain the forward end of the device in suspended relation and substantially in 70 the same plane as that of its supported rear end, and a relatively movable charge receiving member disposed within the delivering device and pivoted in its suspended forward end for tilting movement to unload the 75 charge.

6. In combination, a charge delivering device provided with supporting wheels adjacent its rear end, a guide means mounted on a suitable support above said device, a 80 rigid connecting member extending from the device to slidably engage the said guide means, and coöperating therewith to guide and sustain the forward end of the device in suspended relation and substantially in 85 the same plane as that of its supported rear end, a relatively movable charge receiving member disposed within the delivering device and pivoted in its suspended forward end for tilting movement to unload the 90 charge, and a positive means for imparting reciprocative movement to the delivering device.

7. In furnace charging apparatus, a charge delivering device supported adjacent 95 its rear end for travel along the charging platform, means disposed above the platform for suspending the front end of the device and guiding the same in its travel to overhang the charging hole of the furnace, 100 a relatively movable charge receiving member normally disposed in a horizontal position in the said device and axially mounted in the forward suspended end, co-acting stop means at the supported end of the device, 105 for defining the normal position of the receiving member, and means for tilting the said member to unload the charge.

8. In combination with parallel sets of upper and lower guiding tracks, of a furnace charging apparatus comprising a charging device having its rear end suitably supported for travel along the lower tracks, and having its front end suspended from and guided by the upper set of tracks, 110 and means for imparting reciprocative movement to the device for travel within the guiding tracks, substantially as described.

9. In combination with the furnace charging platform, of a furnace charging device 120 embodying a movable carrier having its front end suspended clear of the platform and its rear end suitably supported for travel along the platform toward the door of the furnace, and a charge receiving member pivotally mounted in the suspended front end and tiltable relatively of the supported rear end, substantially as described.

10. In combination with the furnace charging platform, and a guide track dis- 130

posed above said platform; of a charging carrier frame having one end suitably supported on said platform for travel therewith along and its other end suspended from the 5 track, and a charge receiving member axially mounted in said suspended end and tilttable on its axis relatively of the supported end.

11. In combination with the furnace 10 charging platform, of a furnace charging device comprising a carrier frame having its rear end suitably supported on the said platform for travel therewith along in a direction toward the door of the furnace and its front 15 end suspended independently of said rear end and platform and free of said platform, and a charge receiving member axially mounted in said suspended front end and capable of being tilted relatively of the supported rear end to unload the charge at 20 variable points in the line of travel of the device.

12. In combination with the furnace charging platform, of a furnace charging 25 device comprising a movable carrier having two fixed axes of wheeled support for travel along the platform and a suspended front end normally overhanging the platform and adapted to project into the door of the furnace 30 at one limit of its travel, and a tilttable charge skip receiving member pivotally mounted in the suspended front end of the carrier and conformed to receive the wheels of the skip.

35 13. In a device of the character described, the combination of the upper and lower related tracks disposed to extend in a direction toward the furnace, a furnace charging device comprising a carrier operatively associated with the upper track and suitably supported for travel along the lower track whereby the device has guided movement toward the furnace during its said travel, and a tilttable charge receiving member 40 mounted in the carrier.

45 14. In a furnace charging apparatus, a charge delivering device provided with wheels adjacent its rear end, an overhead guide track, said device having a front end 50 supporting member extending upwardly therefrom to slidably engage said track, and means pivotally connected with said member for reciprocating said device.

55 15. In a furnace charging apparatus, a charge skip receiving and delivering device comprising in combination a movable carrier having a rear abutment, and a tilttable inner frame member conformed to receive the wheels of the skip and pivotally mounted 60 adjacent the front end of the carrier and having its free end normally resting upon the said abutment and tilttable relatively thereto.

65 16. In a device of the character described, the combination with parallel sets of tracks

disposed to extend in a substantially horizontal direction toward the furnace, of a furnace charging device comprising a charging carrier having a tilttable charge receiving member pivotally mounted therein, said 70 carrier being constructed and arranged to project into the furnace at one limiting position and suitably supported for travel along one of the tracks and operatively engaging with the other of the tracks, whereby the carrier is maintained in a substantially horizontal relation in its travel to and from its said limiting position, and means for tilting the charge receiving member. 75

17. In a device of the character described, 80 the combination with a substantially horizontal charging platform and its track, of a charging device comprising a carrier engaging said track and a tilttable charge receiving member mounted in the carrier, 85 means for advancing the said device along the platform track toward and into a projecting relation with reference to the furnace, and a supporting means coöperating with the track for maintaining the horizontal 90 relation of the carrier during said movement, said carrier being provided with a member extending to engage said last mentioned means.

18. In a device of the character described, 95 the combination with a substantially horizontal charging platform, of a wheeled charging carrier having a tilttable charge receiving member mounted therein, a guide means engaged by said carrier, means for 100 advancing and retracting said carrier along said platform toward and from the door of the furnace, and a tilting device for said receiving member operable to tilt said member to unload the charge into the furnace, 105 said guide means serving to maintain the horizontal relation of the carrier.

19. In furnace charging apparatus, and in combination with the charging platform, of a charge delivering carrier supported adjacent its rear end and adapted for travel along the platform into the door of the furnace, means coöperating with said platform for suspending the front end of the carrier whereby on passing through the door of the 115 furnace said front end overhangs the charging hole of the furnace, and a charge receiving member pivotally mounted in said carrier and capable of being tilted to unload the charge into the hole of the furnace. 120

20. The combination with the furnace and its charging platform, of a charging device for the furnace comprising a carrier and a charge receiving member pivotally mounted therein, said carrier having its rear end suitably supported for travel along the charging platform toward the furnace and a suspended forward end adapted to project into the charging hole of the furnace at one 125 limit of its travel, said receiving member be- 130

ing tiltable on its pivotal axis to unload the charge when the carrier is in its projected relation.

21. In an apparatus of the character described, the combination with the charging platform, of a guide track adjacent thereto, a furnace charging device comprising a tiltable charge receiving member and a carrier having two fixed axes of support located therein and disposed in relatively different horizontal planes for co-active movement toward and from the furnace, and

wheels mounted at the respective axes operatively disposed with reference to said platform and guide track, respectively.

In testimony whereof we have hereunto signed our names in the presence of the subscribed witnesses.
